Lurelle Guild, Darien, Conn., assignor to Aluminum Company of America, Pittsburgh, Pa., a corporation of Pennsylvania

Application March 17, 1954, Serial No. 29,581

Term of patent 14 years

(Cl. D44—15)

To all whom it may concern:

Be it known that I, Lurelle Guild, a citizen of the United States, residing at Darien, in the county of Fairfield and State of Connecticut, have invented a new, original, and ornamental Design for a Casserole Holder or Similar Article, of which the following is a specification, reference being had to the accompanying drawing, forming a part thereof, in which:

Fig. 1 is a top plan view of a casserole holder showing my new design; and

Fig. 2 is a side elevation view thereof in partial cross section.

I claim:

The ornamental design for a casserole holder or similar article, substantially as shown.
